[57] CLAIM

The ornamental design for a double-sided illuminated mirror, substantially as shown and described.

DESCRIPTION

FIG. 1 is a front perspective view of a double-sided illuminated mirror showing my new design with the mirror angled slightly relative to the housing and in a pivoted position;

FIG. 2 is a front elevational view thereof with the mirror and housing in a vertical position;

FIG. 3 is a left side elevational view thereof, the side opposite being a mirror image;

FIG. 4 is a top plan view thereof;

FIG. 5 is a rear elevational view thereof; and,

FIG. 6 is a bottom plan view thereof of the stand member.
